(57) **CLAIM**

The ornamental design for a microtiter plate, as shown.

DESCRIPTION

FIG. 1 is a front perspective view of a microtiter plate according to a first embodiment;

FIG. 2 is a further front perspective view of the microtiter plate according to the first embodiment;

FIG. 3 is a top view of the microtiter plate according to the first embodiment;

FIG. 4 is a bottom view of the microtiter plate according to the first embodiment;

FIG. 5 is a side view of the microtiter plate according to the first embodiment;

FIG. 6 is another side view of the microtiter plate according to the first embodiment;

FIG. 7 is still another side view of the microtiter plate according to the first embodiment;

FIG. 8 is a front perspective view of a microtiter plate according to a second embodiment;

FIG. 9 is a further front perspective view of the microtiter plate according to the second embodiment;

FIG. 10 is a top view of the microtiter plate according to the second embodiment;

FIG. 11 is a bottom view of the microtiter plate according to the second embodiment;

FIG. 12 is a side view of the microtiter plate according to the second embodiment;

FIG. 13 is another side view of the microtiter plate according to the second embodiment; and,

FIG. 14 is still another side view of the microtiter plate according to the second embodiment.

The broken lines showing a side wall of each well of the microtiter plate are for illustrative purposes only and forms no part of the claimed design.
